UNITED STATES PATENT OFFICE.

CHARLIE L. SOCKWELL, OF NORTHWILKESBORO, NORTH CAROLINA.

GRAIN-SHOE.

1,289,945.

Specification of Letters Patent. Patented Dec. 31, 1918.

Application filed March 29, 1917. Serial No. 158,311.

To all whom it may concern:

Be it known that I, CHARLIE L. SOCKWELL, a citizen of the United States, residing at Northwilkesboro, in the county of Wilkes 5 and State of North Carolina, have invented a new and useful Grain-Shoe, of which the following is a specification.

The object of my invention is to provide an improved grain shoe or screen cleaner for 10 corn mills; to provide novel means for allowing cobs and nubbins to pass out of the hopper to the extreme upper end of the grain shoe and to arrange same so as to prevent choking of the feed. It is a further 15 object of my invention to provide a novel valve within the grain shoe so that the shoe may be quickly adjusted for screening different kinds of material or grain. It is a further object of my invention to provide a 20 novel means for regulating the operation of the grain shoe, as set forth in the accompanying drawing illustrative of the invention.

I attain these objects by the mechanism 25 illustrated in the accompanying drawings, in which—

Figure 1 is a longitudinal section of the entire device applied to a corn mill; Fig. 2 is a top plan of my improved grain shoe; 30 Fig. 3 is a section on line 3—3 of Fig. 1; Fig. 4 is a section on line 4—4 of Fig. 1; and Fig. 5 is an end elevation of the lower mouth end of the grain shoe.

Similar reference characters designate 35 similar parts throughout the several views.

Referring to the accompanying drawings, I provide a grain shoe 1, as shown in the drawing, having a sheet metal bottom 2, a suitable intermediate fine screen 3, and an 40 upper suitable screening member 4, which may be of wire screen or perforated tin. At the lower end of the grain shoe in the lowermost chamber, I provide a novel valve 5 adjustably secured by fastening member 6. 45 When valve 5 is in the position shown in Fig. 2 the material entering the lowermost chamber of the grain shoe is guided out through mouth 7, illustrated in Fig. 5; and when valve 5 is in reverse position the ma- 50 terial in the lowermost chamber is guided out through mouth 8, as shown in Fig. 4. These mouths open into passages leading out of the mill in different directions, such pas- 55 sages being the same as heretofore employed in mills of this type. The upper end of the grain shoe is provided with a novel hopper-

like casting 9 supported in a plane above and inclined downwardly toward the upper end of the grain shoe.

To regulate the flow of material from the 60 main hopper 10 to the hopper-like casting 9, I provide a sleeve 11, which is longitudinally adjustable relative to the mouth of the hopper 10 and supported by a fork 12 which engages projections 13 on sleeve 11. 65 Fork 12 is pivotally mounted on a suitable support 14, and its position, and consequently that of sleeve 11, is regulated by hand adjusting screw 15 and by a suitable 70 spring 16.

I provide a suitable shoe casting or arm 75 18 which is attached to the upper end of the grain shoe to operatively connect it with the shoe vibrator 19. The latter member is pivotally mounted and provided with a ball at one end which is mounted in a suitable ball and socket member 20. Adjustably attached to the ball and socket member 20 is a suitable eccentric rod 21 which is driven 80 by any suitable eccentric from a revolving shaft of the mill.

In operation the vertical movement of eccentric rod 1 and member 20 causes a vibration of the pivotally mounted shoe vibrator 19. The latter is pivotally attached 85 to shoe casting 18, and that member in turn is rigidly secured to the grain shoe. A vibratory movement is thus imparted to the grain shoe. Material dropped into hopper 10 flows down on to member 9. The 90 amount of the flow is regulated by the position of sleeve 11. The position of sleeve 11 is adjusted or regulated by member 15, as shown in Fig. 3. Material having entered the hopper-like casting 9 flows thence into the upper end of the grain shoe onto screening member 14. It is thus possible to utilize the entire length of the grain shoe for 95 screening purposes. Cobs and nubbins which fail to pass through screening member 4 are carried off through a suitable mouth 22, as shown in Fig. 2. Of the mass of grain or material passing through screening member 4 the finest also sifts through the finer screen 3 and thence out through mouth 8, being diverted by valve 5 when that member is in the position shown in solid lines in Fig. 4, while the coarser grain flows out through mouth 7. Under other circumstances, that is, when a different kind 100 of grain is used and it is desired to divert the grain in the lowermost chamber to 105 110

mouth 7, this is accomplished by moving valve 5 to the position shown in dotted lines in Fig. 4. This can be accomplished almost instantly by means of locking member 6. 5 In other words, material that has passed through screening member 3 to the lower-most chamber is diverted into the mill, whereas when valve 5 is in its reverse position the material in that same chamber is 10 diverted into the dust pan.

I claim—

1. A grain shoe having a plurality of screening members of different screening capacity, in combination with a hopper-like 15 casting secured to the upper end of the grain shoe and inclined downwardly toward that end, said casting being spaced above the screening member and having its uppermost portion substantially elevated from 20 the grain shoe, whereby the material is delivered to the extreme upper end of the grain shoe.

2. In a device of the class described, the combination of a hopper, a grain shoe, 25 means operatively connected with the grain shoe for agitating same, a hopper-like casting secured to the upper end of the grain shoe at an inclination thereto for conveying material into the extreme upper end of the 30 grain shoe, the aforesaid casting being spaced above the grain shoe and having its uppermost portions substantially elevated, a hopper mouth spaced from but in proximity to the aforesaid casting, and means ad-

justably extending below the aforesaid hopper mouth of a mill for regulating the amount of material delivered into the grain shoe. 35

3. In a device of the class described, the combination of a grain shoe, a hopper-like 40 casting secured to the upper end of the grain shoe and inclined in an opposite direction thereto for conveying material into the extreme upper end of the grain shoe, the said casting having its uppermost portion 45 substantially elevated above the grain shoe, means operatively connected with the grain shoe for agitating the same, and a mill hopper mouth in proximity to which the aforesaid grain shoe is mounted. 50

4. In a device of the class described, the combination of a grain shoe comprising a plurality of superposed screens of different mesh and having a valve-controlled mouth between said screens and an independent 55 mouth above the upper screen opening out at one side of the grain shoe, a hopper-like casting secured to the upper end of the grain shoe at an inclination thereto for conveying material into the extreme upper end of the 60 grain shoe, the said casting having its uppermost portion substantially elevated above the screening member the casting being inclined toward the upper end of the grain shoe to deliver material to the extreme upper end thereof, and means for 65 adjusting the inclination of the grain shoe.

CHARLIE L. SOCKWELL.
